(57) **CLAIM**

The ornamental design for a tool dispenser having a serrated spine, as shown.

DESCRIPTION

FIG. 1 is an isometric view of a tool dispenser having a serrated spine constructed in accordance with the present invention;

FIG. 2 is a first end planar view of the tool dispenser having a serrated spine of FIG. 1;

FIG. 3 is a second end planar view of the tool dispenser having a serrated spine of FIG. 1;

FIG. 4 is a first side planar view of the tool dispenser having a serrated spine of FIG. 1;

FIG. 5 is a second side planar view of the tool dispenser having a serrated spine of FIG. 1;

FIG. 6 is a top planar view of the tool dispenser having a serrated spine of FIG. 1; and,

FIG. 7 is a bottom planar view of the tool dispenser having a serrated spine of FIG. 1.
